PRINTER'S PLATE CLAMPING DEVICE

Siegmund Roesner, Oak Park, Ill.

Application September 30, 1935, Serial No. 42,771

4 Claims. (Cl. 101—385)

This invention relates to clamp devices for securing electrotypes and like printing plates in place on the form bed of a printing press, and has reference more particularly to a known type 5 of so-called "drop-in" hooks which are employed in connection with a honeycomb type of base block.

Honeycomb base blocks of the type above mentioned are formed with rows of closely spaced 10 holes of uniform diameter, each of the holes being undercut at or near its lower end to provide an annular shoulder. One known type of drop-in hook employs a pair of members pivotally connected at their lower ends that are 15 insertable from above in the hole, one of the members having on its upper end a lip or jaw to engage with the edge of an electrotype plate or the like, and a screw mounted in a threaded 20 hole in its upper end portion and jaw, and the other member having an inclined surface on its upper end that is engaged by the tip of the screw as the latter is forced downwardly by a key 25 wrench so as to spread the upper portions of the members and force the lip or jaw into clamping engagement with the plate, said other member also having on its lower end a lateral toe that, through engagement with the shoulder on the wall of the hole, prevents a rising movement 30 of the device during the locking operation.

30 My present invention relates to the above-named type of drop-in hook and is based on the broad mechanical principle thereof; but has for its object to provide a simpler, less expensive, and more efficient device than has hitherto 35 been known, the reduction in the cost of manufacture being due mainly to the fact that the principal body member of the device can be made on a punch press by a single stamping operation. Enormous quantities of plate clamps are required in any large printing establishment, so 40 that the item of cost is a very material factor.

An approved and preferred form of my invention is illustrated in the accompanying drawing, in which—

45 Fig. 1 is a vertical section through a fragment of a base block and electrotype plate thereon showing my improved clamp, also in section, applied thereto; the drawing showing the device about twice life size.

50 Fig. 2 is a top plan view of Fig. 1.

Fig. 3 is a fragment view similar to Fig. 2 but showing the device in collapsed position.

55 Fig. 4 is a longitudinal vertical section through the body member.

Fig. 5 is a similar section through the expander arm.

Fig. 6 is a side elevation of the device as viewed from the left of Fig. 3.

Fig. 7 is an opposite side elevation as viewed from the right of Fig. 3.

In the drawing, 10 designates as an entirety a fragment of the honeycomb base block, and 11 designates the narrow undercut annular shoulder formed in each hole of the block. 12 designates an electroplate having the usual beveled edge 13 that is mounted on the base 10.

The drop-in hook or clamp comprises only four parts, consisting of a body member 14, an expander arm 15, a hinge pin 16 by which the lower ends of the members 14 and 15 are pivotally united, and a screw 17. The body member 14 is of substantially semi-cylindrical form in cross section, as shown by Fig. 2, and integral with its upper end is a transversely extending 20 lip or jaw 18, the outer face of which has a bevel corresponding to the bevel 13 of the plate 12. At the base of the plate-engaging side of the jaw 18 is a transverse groove 19. About midway of the body member 14 the material is cut 25 and punched rearwardly to form an integral internal cam 20, and on the lower end of the body member, below the cam 20, is a narrow hook 21. The opposite side walls of the body member 14 at their lower end are formed with holes 22 30 for engagement with the hinge pin 16.

The expander arm 17 is formed in its upper end with an internally threaded hole 23 and, directly below the hole, with a longitudinal groove or recess 24, the purpose of which is two-fold— 35 to provide space for the downward travel of the screw, and also space to receive the projecting cam 20 when the two members 14 and 17 are collapsed as shown in Figs. 3 and 7. The lower end of the arm 17 fits between the opposed sides 40 of the body member 14 and has a hole 25 that registers with the holes 22 of the body member, the registering holes receiving the hinge pin 16. Engaged with the threaded hole 23 is the screw 27 formed with a smooth rounded lower end or 45 tip 28 that is adapted for sliding engagement with the cam 20. In the upper end of the screw is a polygonal socket 29 that receives the ordinary key wrench 30 such as is employed for locking clamps of this type in the base block.

50 When using the device, the screw 27 is first backed out to the point where its tip is substantially flush with the lower end of the threaded hole 28. In this collapsed position of the parts the expander arm 17 is nested in the body mem- 55

ber 14, as shown in Fig. 3. The device is then, either by the thumb and finger or by a special tool sometimes used, dropped into the hole and adjusted sidewise until its lip or jaw 18 overlaps 5 the beveled edge of the plate 12. The key wrench is then applied to the screw and the latter is screwed downwardly, the sliding contact of its tip with the cam 20 expanding or spreading the upper portions of the members 14 and 17 until the 10 upper end of the arm 17 strikes the opposite side of the wall of the hole, as shown in Fig. 1. At the same time, this thrust engagement of the screw with the cam forces the hook 21 of the body member beneath the shoulder 11 of the hole, as 15 shown in Fig. 1, so that the device is securely locked from accidentally falling out of the hole. The groove or kerf 19 at the base of the jaw 18 permits the jaw to grip the plate even though the 20 lower edge of the latter may slightly overlap the edge of the underlying hole, as shown in Fig. 1. When the electroplate 12 is to be removed, a simple backing off of the screw enables the parts to 25 be collapsed and thus readily picked out of the hole.

As hereinabove stated, the body member 14 may be made from sheet metal by a single operation in a punch press having a suitably shaped die therefor, while the cooperating expander arm 30 17 can also be made from round stock by a few simple machine operations. This makes the device very inexpensive to manufacture, without any sacrifice of efficiency.

I claim:

1. A printer's expandible drop-in hook adapted for use in the holes of a honeycomb base block, comprising a body member formed with a plate-engaging jaw on its upper end, a cam on its intermediate portion on the opposite side from said 35 jaw, and a hook on its lower end on the same side as said jaw, and an expander, comprising an arm pivoted at its lower end to the lower end of said body member, and a screw in its upper end adapted to be screwed downwardly in sliding contact 40 with said cam to thereby spread the upper portions of said body member and arm and force said hook beneath a shoulder on the wall of the hole. 45
2. A printer's expandible drop-in hook adapted for use in the holes of a honeycomb base block, comprising a body member of substantially semi- 50

cylindrical form in cross section having a plate-engaging jaw on its upper end, an internal cam on its intermediate portion on the opposite side from said jaw, and a hook on its lower end on the same side as said jaw, and an expander, comprising an arm pivoted at its lower end in the lower end of said body member, said arm shaped to substantially nest within said body member when the two are collapsed, and a screw in the upper end of said arm adapted to be screwed downwardly in sliding contact with said cam to thereby spread the upper portions of said body member and arm and force said hook beneath a shoulder on the wall of the hole. 5
10
15

3. A printer's expandible drop-in hook adapted for use in the holes of a honeycomb base block, comprising a body member formed with a plate-engaging jaw on its upper end, an integral internal indented cam substantially mid-length thereof and on the opposite side from said jaw, and an integral hook on its lower end on the same side as said jaw, and an expander, comprising an arm pivoted at its lower end to the lower end of said body member and a screw in its upper end formed with a smooth blunt point adapted to slidingly contact with said cam as said screw is advanced to thereby spread the upper portions of said body member and arm and force said hook beneath the shoulder on the wall of the hole. 20
25
30

4. A printer's expandible drop-in hook adapted for use in the holes of a honeycomb base block, comprising a body member of substantially semi-cylindrical form in cross section having a plate-engaging jaw on its upper end, a transverse groove at the base of the plate-engaging side of said jaw, an internal cam on its intermediate portion on the opposite side from said jaw, and a hook on its lower end on the same side as said jaw, and an expander, comprising an arm pivoted at its lower end in the lower end of said body member, said arm shaped to substantially nest within said body member when the two are collapsed, and a screw in the upper end of said arm adapted to be screwed downwardly with its tip in sliding contact with said cam to thereby spread the upper portions of said body member and arm and force said hook beneath an undercut shoulder on the wall of the hole. 35
